UNITED STATES PATENT OFFICE.

ORIN H. DAVISON, OF CHICAGO, ILLINOIS, ASSIGNOR TO BLAIR ENGINEERING COMPANY, OF CHICAGO, ILLINOIS, A CORPORATION OF NEW YORK.

REVERSING APPARATUS FOR REGENERATIVE FURNACES.

1,269,165.

Specification of Letters Patent. Patented June 11, 1918.

Application filed June 5, 1917. Serial No. 172,907.

To all whom it may concern:

Be it known that I, ORIN H. DAVISON, a citizen of the United States, residing at Chicago, in the county of Cook and State of Illinois, have invented a new and useful Improvement in Reversing Apparatus for Regenerative Furnaces, of which the following is a specification.

The primary object of my invention is to improve the mechanism of the apparatus of Letters Patent of the United States No. 929,277, granted July 27, 1909 to Thomas S. Blair, Jr., for a reversing apparatus for regenerative furnaces, to the ends of materially simplifying the construction, facilitating the switching of the elbow-like flue-connecting ducts, and greatly decreasing the weight of the apparatus, reducing the cost of its manufacture, and the expense of its maintenance and operation.

The following general description of the patented apparatus and its operation will facilitate comprehension of the present improvements and avoid the need of herein illustrating and describing them with reference to more than one of the reversing flue-terminal connecting ducts, its attending parts and features coöperating with it:

Swinging ducts are provided for reversing the gaseous fuel and combustion-supporting air through the furnace including the checker-work underneath, all being under the influence of the stack-draft, and each of the two gas-conducting flues has its communication with the gas-supply equipped with a shut-off valve. Each duct is rotatably and tiltably mounted at one end on the water-sealed terminal of a flue and is adapted to be seated at its opposite end alternately in water-sealed terminals of the two other flues, after being tilted on its one end to withdraw the opposite end from its seat on one terminal preparatory to the turning to register its swinging end with and seat it at the other terminal for reversing the course of the gas or air through the furnace to the stack. The terminal of each air-flue is equipped with a lid or valve hinged for adjusting it to regulate the admission of air when the valve is open and to be automatically raised out of the way of the swinging end of the respective duct in being switched from the terminal of one flue to that of the other, whether these latter be air or gas flues. For raising the swinging ends

of ducts out of their seats preparatory to turning them for the switching purpose, a power-cylinder is provided on a superstructure or elevated working platform extending over the ducts; and for turning the ducts, after being thus tilted, to switch them to their reversing positions, they are provided about their axially rotatable ends with cables connected with piston-mechanism for switching the several ducts simultaneously.

These ducts are very heavy, each weighing several thousand pounds, so that the matter of tilting to raise them for the aforesaid purpose tends to strain the mechanism; and in reseating it is difficult to so control them in lowering as to avoid their dropping heavily against their seats with the liability of smashing and disorganizing the mechanism. To overcome these difficulties I have provided a loop-form of truck having cam-ways at its ends and preferably located between the axially rotating and swinging duct-ends for gradually raising and lowering the swinging end of the duct out of and into its seat in initially turning and registering it, and guiding the duct to its reversing position while being switched by the application of suitable power; and this constitutes the principal feature of my improvement, and is, with other features, hereinafter described as illustrated in the accompanying drawings, in which:-

Figure 1 is a plan view showing my improvements as they may be applied to a stack-flue terminal and a pair of air-flue terminals, the switching duct being represented partly in section on line 1—1, Fig. 2, and partly by dotted lines; Fig. 2 is a section on line 2—2, Fig. 1, and Fig. 3 shows the same by a broken sectional view, with the duct in tilted position for swinging it; Fig. 4 is a view in front elevation of the showing in Fig. 1; Fig. 5 is a broken view of a section on line 5—5, Fig. 1; Fig. 6 is an enlarged partly broken and sectional plan view showing a desirable form of electrical power mechanism for swinging the duct, and Fig. 7 is a diagram showing the electric switch-containing circuits.

The flue-terminal 9 is surmounted by an annular trough 10 forming a water-seal. The elbow-like duct 11 is provided about its end registering with the terminal 9, with an internally-flanged thimble-like extension 12 to dip into the water-seal, and it carries

wheels 13, 13 journaled to project at diametrically-opposite points on the extension 12 to ride on the annular track afforded by the outer wall of trough 10 and enable the duct to be tilted on the fulcrum afforded by the journals of the wheels 13. Each of two air-flue terminals, 15 and 16, with which the duct co-operates, is topped by an annular trough 17 forming a water-seal, these two troughs being each like the trough 10; and the swinging end of the duct being also provided with an extension 12, like that about the opposite end, to dip into the respective trough 17. A loop-shaped track 18 is supported to extend underneath the arch formed by the duct and thus between and preferably about midway between the duct-ends. This track is of loop form for the purpose herein-after explained; and it terminates at each end in a cam-way 19. A wheel 20 is journaled on a stud 21 projecting backwardly from the inner face of the swinging end of the duct to ride within and along the track and up and down the cam-ways, each of which forms a seat for the wheel when at that end of the track.

For swinging the duct into registration with either flue-terminal 15 or 16 from the other, it is turned in the proper direction 30 on its track on the terminal 9, thereby riding the wheel 20 up the inner side of the respective cam-way to tilt the duct on the journals of the wheels 13 and raise its swinging end out and clear of the respective trough 17, when the continued turning 35 of the duct causes the wheel 20 to travel along the horizontal intermediate track-section, which guides the duct to the other cam-way, down the inclined inner side of which 40 it continues, to become seated, whereby the duct is tilted forward and enters at its swinging end into the adjacent water-seal trough, with which it then registers. The duct had best be counterweighted to reduce 45 its resistance to tilting by movement along the cam-ways and take its weight off the track, and a suitable counterweight (not shown) may be employed for the purpose. One of the loops 22 shown to be provided 50 on the duct, and which are used for attaching cables to that very heavy member for handling it in the erection and in other connections, may be used for attachment of such counterweight, as through the medium 55 of a cable passing over pulleys on the superstructure or elevated working platform referred to. The loop-form of the track 18 permits the duct to be counterweighted, without resultant excessive tilting, since the 60 upper track-section prevents raising of the swinging end of the duct beyond requirement for taking it out of the cam-ways. This counterweighting has the advantage of 65 reducing, by more than one-half, the weight to be overcome in tilting the duct, thereby

economizing in the power required to be exerted for the purpose; and it prevents over-travel of the wheel 20 in traversing the track and acts as a brake on the wheel in seating itself in a cam-way. The wheel is 70 shown to be double-flanged to prevent end-wise movement of the duct in switching.

Power for operating the duct may be hand, hydraulic, steam, compressed air, or electric. The power represented and which 75 is preferred for the purpose is electric; and following is a description thereof, with particular reference to Figs. 6 and 7:

An electric motor 8 carries a pinion 24 on its shaft for driving gears in a housing 23. 80 This pinion meshes with a gear-wheel 25 keyed to a sleeve 26 loose on a shaft 27 journaled in the housing and carrying on one end a gear-wheel 28 and on its opposite end a crank 29. An extension of the sleeve 26 85 is formed as a pinion 30 meshing with a relatively large gear-wheel 31 keyed to a sleeve 32 which is keyed to a shaft 33 journaled in the housing. This sleeve 32 has an extension formed as a pinion 34, which 90 meshes with a gear-wheel 35 like the gear 31 and keyed to the shaft 27.

The crank 29 has a link-connection 36 with the stud 21 on the swinging duct-end; and rotation of the motor-shaft, always in 95 the same direction, swings the duct from either to the other of the terminals 15 and 16.

The electric switch in circuit with the motor is illustrated in Fig. 7, the switch being 100 upon the upright member of a suitable support A (Fig. 6), comprises a central metallic ring 37, a partial ring 38 of metal concentric therewith and an outer partial ring 39 of metal concentric with the inner ring 105 37 and overlapping at its ends those of the partial ring 38. These contact-forming rings are on a plate 40 of insulating material secured on the aforesaid support-member, in which is journaled a shaft 41 110 carrying on its inner end a gear 28a like and meshing with the gear 28, and on its opposite end a spring-pressed contact-brush 42 to co-operate with the switch-rings. With the circuits as represented in Fig. 7 and the 115 brush bridging the ring 37 and partial ring 39, the current comes in on the wire w, closed by one arm of a throw-switch 43, passes through the motor and thence by way of the ring 37, brush 42 and partial ring 39 120 to the return-wire w', cutting out the motor when the brush 42 reaches a position, beyond the respective end of the partial ring 39, and connecting the ring 37 and partial ring 38, which position it attains at the end 125 of the throw in one direction of the swinging duct produced by the crank 29 in turning one-half revolution, and seating the duct-end in the trough on one terminal. To reverse the duct, the switch 43 is thrown to 130

cause its one arm to close the line w at a branch w^2 therein, and the other arm to connect the wire w^1 with a wire w^3 leading to the partial ring 38, thereby connecting the wires w^1 and w^3 and closing the circuit over wire w through the motor, and over the ring 37, brush, partial ring 38 and wire w^3 to the return-wire w^1 , thus energizing the motor to turn the crank through its remaining 10 half-revolution and swing the duct to the end of its throw in the opposite direction for seating it in the trough on the other terminal into registration with the latter.

Each flue-terminal 15 and 16 is provided 15 with a hinged lid or cover 44 having the hinge-pintle 45 journaled in ears 46 on the respective trough. An arm 47 extending from each pintle and connected with the outer face of the respective lid 44 carries on 20 its outer end a pin 48, with which one end of a link 49 is pivotally connected, the other link-end being pivotally connected with the stud 21, as shown in Fig. 1. The lids are 25 adapted to extend, for closing the flue-terminals, over the inner walls of the respective troughs and dip at their annular lips or flanges into the water therein to seal the closure; and they are so arranged that when the duct is turned from one flue-terminal to 30 register with the other, the lid on the latter is raised, by its link-connection with the stud 21, out of the way of the swinging end of the duct to enable seating thereof without obstruction, and the link-connection with the 35 stud of the other lid causes the latter to be lowered on its hinge over the inner wall of the adjacent trough to close that flue-terminal. When the flues having the terminals 15 and 16 are air-flues, it is desirable to 40 adapt the lids to act as valves for regulating the admission of air into the flues. For that purpose each link is provided in its outer end with a longitudinal slot 50, through 45 which the pivotal connection of the respective arm 47 is made; and each cover has attached to it one end of a cable 51, the opposite end being adjustably fastened to any suitable overhead device, which may be on the aforesaid superstructure. By properly 50 adjusting the length of the cable, the hinged cover may be arrested by it to desired extent, short of closing the terminal. With the pivotal connection of the arm 47 and link in a slot 50, the resultant lost motion in the one 55 direction of the respective link will always permit the lid to be raised out of the way of the duct in seating and, in the other direction, will not engage the pivot-pin in the slot after the lid has closed to the extent permitted 60 by its adjusting cable 51. As will be understood, the lid on one gas-flue terminal should be fully closed when that on another such terminal is fully open, so that for the lids on such terminals there are no slots in 65 their operating links with which each re-

spective arm 47 should then be pivotally connected at a fixed point; and no cables 51 are used.

To operate the apparatus for swinging the duct from its illustrated position of connecting the terminals 9 and 15 to that of connecting the terminals 9 and 16, the switch 43 is thrown to the points x , x^1 (Fig. 7), thereby energizing the motor to drive the gearing in the housing 23 and turn the crank 29 to 70 ride the wheel up the inclined side of the cam-way 19, in which it is shown to be seated in Fig. 4 and along the track 18 and thence down the inclined inner side of the other cam-way 19 until seated therein. Thus 80 the duct is tilted backwardly on the journals of the wheels 13 to raise the swinging duct-end, while supported by the respective cam-way, out of the water-seal trough of the flue-terminal 15 and 85 carry it along the horizontal section of the track 18 until it attains the other cam-way, down which the wheel rides, supporting the duct at that end until seated, to enter the duct-end into the adjacent trough 17. To 90 swing the duct from the position last described to that in which the drawings represent it, the switch 43 is thrown to the points x^2 , x^3 to again energize the motor. Either movement of the duct, the links 49 95 being connected with the stud 21, closes the lid on the flue-terminal which the duct is leaving and raises the other lid to remove it out of the way of the duct-end in approaching its seat in the adjacent trough 17. 100

By riding the duct along the cam-ways, cables and their rigging for tilting and turning it, shown and described in the aforesaid patent, are dispensed with, resulting in economy and simplification of the apparatus; 105 raising and lowering the swinging duct-end out of and into registration with the flue-terminals is gradual and it is guided in the meantime by the cam-ways, as it is by the intermediate section of the track 18 while the 110 wheel 20 is riding therein; and the lowering of the duct to a flue-terminal with which it is swung into registration is without jar and resultant tendency to disorganize the apparatus. 115

The loop-form of the track 18, with its attendant advantages hereinbefore named, is an improvement upon the apparatus for the same purpose, forming the subject of the application of Thomas S. Blair, Jr., filed 120 concurrently herewith on the 5th day of June, 1917; and this whether the track be located as illustrated and described herein or in the path of the swinging duct-end, both locations being shown in said application. 125 Moreover, my construction is the simpler in dispensing with the turn-table feature of the aforesaid concurrent application.

I realize that considerable variation is possible in the details of construction thus 130

21
specifically shown and described, and I do not intend by illustrating a single specific or preferred embodiment of my invention to be limited thereto, my intention being in 5 the following claims to claim protection upon all the novelty there may be in my invention as fully as the state of the art will permit.

I claim:

- 10 1. In a regenerative-furnace reversing apparatus, the combination of a flue-terminal, a switching duct rotatably and tiltingly supported at one end on said terminal, a pair or flue-terminals alternately with which the 15 opposite swinging end of said duct registers, and a track comprising a loop having cam-ways at its ends for guiding the duct in moving from one to the other of the flue-terminals of said pair.
- 20 2. In a regenerative-furnace reversing apparatus, the combination of a flue-terminal, a switching duct rotatably and tiltingly supported at one end on said terminal, a pair of flue-terminals alternately with which the 25 opposite swinging end of said duct registers, a loop-track having cam-ways at its ends, and a wheel on the duct riding in said track to guide the duct in moving into and out of such registration.
- 30 3. In a regenerative-furnace reversing apparatus, the combination of a flue-terminal, a switching duct rotatably and tiltingly supported at one end on said terminal, a pair of flue-terminals alternately with which the 35 opposite swinging end of said duct registers, a loop-track having cam-ways at its ends and extending between said first-named terminal and said pair of terminals, and a wheel on the duct riding said track to support the duct in moving into and out of such registration.
- 40 4. In a regenerative-furnace reversing apparatus, the combination of a flue-terminal, a switching duct rotatably and tiltingly supported at one end on said terminal, a pair of flue-terminals alternately with which the 45 opposite swinging end of said duct registers, a track comprising a closed loop having cam-ways at its ends and extending between said first-named terminal and said pair of terminals, and a flanged wheel 50 journalled on the duct between its ends to

ride in said loop and confine the duct in the track in moving into and out of such registration.

55

5. In a regenerative-furnace reversing apparatus, the combination of a flue-terminal, a switching duct rotatably and tiltingly supported at one end on said terminal, a pair of flue terminals alternately with which the 60 opposite swinging end of said duct registers, a track comprising a loop having cam-ways at its ends for guiding the duct in moving from one to the other of the flue terminals of said pair, and electric power mechanism including a crank connected with said duct for swinging it.

65

6. In a regenerative-furnace reversing apparatus, the combination of a flue-terminal, a switching duct rotatably and tiltingly supported at one end on said terminal, a pair of flue-terminals alternately with which the opposite swinging end of said duct registers, cam-ways between said first-named terminal and said pair of terminals for guiding the 75 duct at a point between its ends in moving out of and into said registration, and power mechanism for swinging said duct, comprising an electric motor, gear-mechanism geared to the motor shaft and carrying a contact-brush and a crank having a link-connection with said duct, a switch in circuit with said motor and with which said brush contacts, and a circuit-controlling throw switch.

70

7. In a regenerative-furnace reversing apparatus, the combination of a flue-terminal, a switching duct rotatably and tiltingly supported at one end on said terminal, a pair of flue-terminals alternately with which the opposite swinging end of said duct registers, cam-ways and an intermediate track between said first-named terminal and said pair of terminals for supporting the duct at a point between its ends and guiding it in moving from one to the other of the 85 terminals of said pair, and power-mechanism for swinging said duct, comprising an electric motor, gear-mechanism geared to the motor-shaft and carrying a contact-brush and a crank having a link-connection 90 with said duct, a switch in circuit with said motor and with which said brush contacts, and a circuit-controlling throw-switch.
